UNITED STATES PATENT OFFICE.

CHARLES H. BOOTH, OF NEW YORK, N. Y.

LOCOMOTIVE-ENGINE.

SPECIFICATION forming part of Letters Patent No. 583,885, dated June 8, 1897.

Application filed December 18, 1895. Serial No. 572,529. (No model.)

To all whom it may concern:

Be it known that I, CHARLES H. BOOTH, of New York, in the county and State of New York, have invented certain new and useful 5 Improvements in Locomotive-Engines, of which the following is a full, clear, and exact description.

This invention relates to locomotive-engines; and the object is to provide an engine 10 of great power for drawing express or similar trains at high speed and in which the water and fuel carrying capacity is such as to allow for long runs without stopping for coal and water.

15 My invention consists principally in a large tender having driving-wheels and driving-engines receiving steam from the main engine.

It further consists in the construction and novel arrangement of parts, as will be hereinafter specified, and particularly pointed out in the appended claim.

20 Reference is to be had to the accompanying drawings, forming a part of this specification, in which similar characters of reference indicate corresponding parts in all the figures.

25 Figure 1 is a side elevation of a locomotive-engine embodying my invention. Fig. 2 is a diagrammatic plan view thereof. Fig. 3 is a rear elevation of the tender, and Fig. 4 is an 30 enlarged view of a flexible steam-pipe employed.

Referring to the drawings, A designates the boiler of the main engine. A' is the high-pressure cylinder, and A² is the low-pressure cylinder, each being supported on the truck in the usual manner and each having piston connection with the usual drive-wheels. The high-pressure cylinder receives steam from the boiler A through the pipe a and exhausts 35 through the pipe a' into the low-pressure cylinder A², which exhausts through the pipe a² into the smoke-stack, thus utilizing the exhaust to increase the draft through the smoke-stack.

40 The tender B is mounted on the drive-wheels b and a truck b', and in order to get a large water and fuel carrying capacity the tender is projected laterally beyond and overhangs the drive-wheels and truck as shown 45 in Figs. 1, 2, and 3, particularly in the latter

figure, and the tender may be made of a length substantially that of the main engine. By this construction the necessary weight will be obtained, notwithstanding the gradual lessening of weight by the consumption of fuel and 55 water.

To the truck b' is attached a high-pressure cylinder B' and a low-pressure cylinder B². The high-pressure cylinder receives steam direct from the boiler A through a pipe b² 60 and exhausts through a pipe b³ into the low-pressure cylinder, which exhausts through a pipe b⁴ into the water-tank, where this exhaust is condensed and serves to heat the water in the tank prior to its use in the boiler. 65 The cylinders B' B² are connected to their drive-wheels in the usual manner.

The pipe b² comprises a flexible connection B³ between the main engine and tender. This connection may consist of swivel-sections connected by ball-and-socket joints b⁵, as plainly indicated in the drawings. Of course the throttle-valve will be so arranged that steam will simultaneously flow through the pipes a 70 b² to the respective pairs of cylinders. 75

Having thus described my invention, I claim as new and desire to secure by Letters Patent—

A locomotive comprising a main engine, a high-pressure cylinder located on the truck 80 of the main engine and receiving steam direct from the boiler on the main engine, a low-pressure cylinder on the truck receiving the exhaust from the high-pressure cylinder and exhausting into the smoke-stack, a tender 85 connected to the rear of the main engine, a high-pressure cylinder on the truck of the tender receiving steam direct from the boiler on the main engine and independently of the cylinders on the main engine, a low-pressure 90 cylinder on the truck of the tender receiving the exhaust of the high-pressure cylinder and exhausting into the water-tank on the tender and drive-wheels for the tender arranged under the overhanging sides of said tender, sub- 95 stantially as specified.

CHARLES H. BOOTH.
